[57]**CLAIM**

The ornamental design for a zipper pull, substantially as shown and described.

DESCRIPTION

FIG. 1 is a perspective view of a zipper pull showing my new design;

FIG. 2 is a perspective view of the zipper pull connected to a zipper slide;

FIG. 3 is a front side elevational view thereof;

FIG. 4 is a left side elevational view thereof;

FIG. 5 is a rear side elevational view thereof;

FIG. 6 is a right side elevational view thereof;

FIG. 7 is a top plan view thereof; and,

FIG. 8 is a bottom plan view thereof.

The broken line showing of the zipper slide in FIG. 2 is included for the purpose of illustrating environmental structure only, and forms no part of the claimed design.
